DESIGN FOR A BOTTLE

Georges Wilmet, Roslyn, N. Y., assignor to The Revlon Nail Enamel Corporation, New York, N. Y., a corporation of New York

Application June 11, 1938, Serial No. 77,773

Term of patent 7 years

To all whom it may concern:

Be it known that I, Georges Wilmet, a citizen of Belgium, residing in Roslyn, county of Nassau, State of New York, have invented a new, original, and ornamental Design for a Bottle, of which the following is a specification, reference being had to the accompanying drawing, forming part thereof:

I claim:

The ornamental design for a bottle, as shown.

GEORGES WILMET.
